UNITED STATES PATENT OFFICE.

CYRUS P. GIFFORD, OF ERIE, PENNSYLVANIA, ASSIGNOR OF TWO-THIRDS TO WILLIAM A. KARLE, OF ERIE, PENNSYLVANIA.

EDUCATIONAL DEVICE.

1,256,997.

Specification of Letters Patent. Patented Feb. 19, 1918.

Application filed June 8, 1917. Serial No. 173,552.

To all whom it may concern:

Be it known that I, CYRUS P. GIFFORD, a citizen of the United States, residing at Erie, in the county of Erie and State of Pennsylvania, have invented certain new and useful Improvements in Educational Devices; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

5 My invention relates to educational devices, the object of which is to teach children addition, subtraction and multiplication.

The features of my invention will appear hereinafter and are illustrated in the accompanying drawings in which:—

Figure 1, is a plan view of an educational device embodying my invention.

Fig. 2, is a like view with a portion of the top plate broken away.

Fig. 3, is a transverse central section of the same.

In these drawings A (see Fig. 3) indicates the bottom plate, which is provided with a raised rib *a* around its perimeter, and a central opening *a'* therethrough. Upon the plate A I place a disk B and upon the ribs *a* I secure the upper plate C having a central opening *c* therethrough. Within the central opening *a'* in the bottom plate A I place the hub D of a thumb-wheel D', said hub D touching the under side of the disk B, and in the opening *c* in the upper plate I place the hub E of an indicator hand E', said hub E and hub D being 40 non-rotatably secured to the disk, preferably by means of screws *e e*, or their equivalent, so that when the thumb-wheel D' or the indicator hand E' is moved, the disk B will rotate in unison therewith.

45 The upper plate C has printed or engraved upon it a dial F divided into 77 radial sub-divisions numbered from 1 to 77 inclusive, in consecutive order, said numbers appearing in a circle G, and in a circle H there is printed or engraved thereon numbers from 1 to 77 inclusive, not in consecutive order, the same being mixed up. There is also printed upon the upper plate C, within the circle J seven groups of numbers running from 1 to 12 inclusive, each group being in-

dicated by a bracket line I, said bracket being numbered from 2 to 7 inclusive; and between the circles of numbers G and H there is printed the letters of the alphabet, said letters being numbered by the figures 60 in the circle K.

The upper plate C is provided with an elongated opening L, and with a small opening M therethrough. The indicator hand E' is provided with an opening e' therethrough, which registers with the circle J so that the numbers in said circle will be visible therethrough; and I also preferably provide said indicator hand with a knob E² whereby it may be moved as desired. The 70 disk B (see Fig. 2) has printed thereon three circles of numbers N, O and P, in radial sub-divisions, corresponding with the radial sub-divisions on the dial F of the upper plate C, the numbers in the circle N on the disk 75 B being respectively the sums of numbers appearing in the corresponding sub-divisions in the circles H and G of the dial F on the upper plate, and the numbers appearing in the several sub-divisions of the circle O on the disk B being the difference between the numbers appearing in the corresponding sub-divisions of the circles H and G of the dial F on the upper plate C. The numbers appearing in the several sub-divisions of the circle P of the disk B represent the products of multiplying the numbers in the several sub-divisions of the circle J by the numbers of the several brackets I.

Upon the disk B between the circles of numbers N and O there is printed a series of names or words, which have relation to the letters of the alphabet and the numbers printed in the circle K, as hereinafter set forth.

95 In operation, the indicator hand E' is turned to point to the numbers 40 and 51 on the dial F, which turns the disk B so that the sum and difference of said numbers, viz: 91 and 11 will appear under the opening L in the dial F, and the product of multiplying the numbers in the circle G by 5, will appear at the small opening M in the dial F, thus 5 times 1 (appearing through the opening e' in the indicator hand E') is 100 105 5, (appearing at the opening M) all as shown by full lines in Figs. 1 and 2.

To find the words and names in the disk B the operation is as follows, viz: Take the name "David" for example: D is numbered 110

4 in the circle K, A is numbered 1, V is numbered 22, I is numbered 9, and D is numbered 4. The sum of 4, 1, 22, 9 and 4 is 40. Turn the indicator hand to point to 40 in the circle G on the dial F and said name will appear at the opening L in the dial F. Likewise any of the words on said disk B can be found.

10 My device is not an adding machine, it is simply an educational device, and the numbers, sums, differences and products are arbitrarily printed thereon.

15 Having thus shown and described my invention so that others can utilize the same, I do not wish to be limited to the exact construction shown and described, as many modifications can be made therein without departing from the scope of my invention; but what I claim as new and desire to secure

20 by Letters-Patent, is:

25 1. In a device of the class described, a dial having a plurality of circles of numbers printed in radial sub-divisions and having an elongated opening therethrough, an indicator hand centrally pivoted in said dial adapted to point to desired numbers on said dial, a disk under said dial secured to and rotatable with said indicator hand, and having printed thereon in radial sub-divisions the sums and differences of the several numbers in the corresponding sub-divisions on said dial, said sums and differences being

visible through said elongated opening in said dial, substantially as described.

2. In a device of the class described, a dial having a circle divided into radial subdivisions, and having groups of numbers in said circle running from 1 to 12 inclusive, said groups being consecutively numbered from 2 upward, said dial having an opening therethrough, an indicator hand centrally pivoted in said dial adapted to be turned to indicate any number in each of said several groups of numbers, a disk under said dial non-rotatably secured to said indicator hand, and having printed thereon figures indicating the product obtained by multiplying the number indicated by the hand by the number of the group, said product appearing at said opening in said dial, substantially as described.

3. In a device of the class described, a dial having an opening therethrough, letters of the alphabet printed on said dial, a circle of numbers for said letters, another circle of numbers from 1 upward, an indicator hand pivoted at the center of said dial, a rotatable disk under said dial and secured to and rotatable with said hand, words printed on said disk in radial sub-divisions, corresponding with the last mentioned circle of numbers, substantially as set forth.

In testimony whereof I affix my signature.

CYRUS P. GIFFORD.
